UNITED STATES PATENT OFFICE.

DONALD PARKER, OF TAMPA, FLORIDA.

BOX-PRESS.

1,293,181.

Specification of Letters Patent.

Patented Feb. 4, 1919.

Application filed June 12, 1918. Serial No. 239,614.

To all whom it may concern:

Be it known that I, DONALD PARKER, a citizen of the United States, residing at Tampa, in the county of Hillsborough and 5 State of Florida, have invented certain new and useful Improvements in Box-Presses, of which the following is a specification.

The present invention relates to improvements in a fruit box press particularly of 10 the type disclosed in Letters Patent No. 985,540.

The present invention has for its principal objects to provide a construction wherein the clamping arms are preferably two in 15 number, one adapted to coöperate with each end of the fruit box and are connected with an equalizing frame movable upon certain operating mechanism whereby a uniform pressure is applied to both ends of the box 20 cover regardless of the height or elevation thereof above the table and within certain limits, thus insuring the applying of the cover to the box and the application of a uniform pressure to the upper layers of fruit 25 for the proper pressing of the same within the box without in any way injuring the pressed or packed fruit.

With the above mentioned and other objects in view, the invention consists in the 30 novel construction and combination of parts hereinafter described illustrated in the accompanying drawings, and set forth in the claims hereto appended, it being understood that various changes in the form, proportion, size, and minor details of construction 35 within the scope of the claims may be resorted to without departing from the spirit or sacrificing any of the advantages of the invention.

40 To more fully comprehend the invention reference is directed to the accompanying drawings, wherein,

Figure 1 is a view in front elevation of the preferred embodiment of my invention. 45 Fig. 2 is a view in end elevation of the apparatus illustrated in Fig. 1.

Referring more particularly to the several views of the drawings, wherein like characters of reference designate corresponding parts, the numeral 1, indicates a suitable base or table on which is positioned the filled box with a cover applied thereto. The base or table is supported preferably at its four corners by the legs 2 and is also supported 50 intermediate of its length by the central support 3. The rear corner supports 2, project

a slight distance above the base or table 1 and suitable guide or brace members 4 are positioned in slight spaced relation thereto and extend parallel therewith forming suitable vertical guides 5 at the inner side of the rear corner supports 2.

A suitable frame 6 extends transversely of the rear corner supports 2, members 4 and guides 5 and the same is angularly bent outwardly or forwardly as at 7 at its outer end 60 providing arms for properly positioning a filled box on the base or table 1 and to insure the closing of a portion of the front of the guides 5. Mounted for vertical reciprocation within the guides 5 are the body portions 8 of suitable pressing members, said body portions being pivotally connected at their lower end as at 9 to the opposite ends 65 of an equalizing frame 10, preferably oblong in plan, said frame being slotted in its center as at 11, and through said slots extends an operating lever or pedal 12 pivotally connected at one end to a rod 12' supported at its ends by the free ends of links 70 13 which are fulcrumed at their opposite ends to a base or fulcrum portion 14. The pedal or lever 12 is provided with a longitudinal slot 15 in the region of its passing 75 through the opening 11 and through said slot 80 extends a suitable transverse member 16 connected to the frame 10 at opposite sides of said slot 11. The raising and lowering 85 of the lever or pedal 12 in turn raises and lowers the equalizing frame 10 and the loose 90 connection between the slot 15 and pin 16 permits of a slight fulcrum or pivotal movement of the frame relatively to the path or movement of the lever, thus permitting the 95 automatic adjustment of the pressing members so that the shoes or arms 17, pivotally mounted as at 18 to the upper ends thereof and overhanging the positioned box will receive equal pressures regardless of the difference in height thereof. Suitable lugs 19 100 project on opposite ends of the frame 10 and in the same are carried adjusting screws 20 adapted to contact with the lower ends of the member 8 to limit the free lateral movement of the frame relatively to said members. Suitable spaced guide members 21 and 22 are carried by the central supporting member 3 and between the same operates a guide pin 23 carried by the outer end 105 of the lever or pedal 12. The guide member 21 is provided with a rack surface 24 for engagement by a pivotal pawl 25 carried on

the lever or pedal 12, said pawl having a foot releasing member 26 which overlies a foot rest 27 on the free end of the pedal, a spring 28 normally maintaining the pawl 5 in engagement with a rack surface 24. A coiled spring 29 is employed for raising the presser arms and pedal or lever to the position as in Fig. 2 on the release of the pawl 25.

By my improved construction it will be 10 apparent that the equalizing frame 10, permits of a limited independent movement of the presser members relatively to the pedal or lever 12, thus compensating for an unevenness in height of the box, to which the 15 cover is to be applied and within which the contents are pressed. The adjusting members 20 limit the movement of the frame 10 relatively to the presser members and the shoes or arms 17 permit of a uniform power 20 or force being applied to the box cover transversely of its end and which is desired to be secured in position on the box proper.

Having thus described my invention what I claim is:

- 25 1. In a box press, a pair of movable cover pressing members, a box support, a fulcrumed lever, a pressure equalizing frame capable of operation by said lever and of free lateral movement relatively thereto, a
- 30 pivotal connection between said frame and each of said cover pressing members, and adjustable means coöperating with said frame and said pressing members for limiting the relative pivotal movement of the
- 35 same.
2. In a box press, a pair of cover pressing members, a guide for each of said members

and relatively to which the same are capable of vertical movement, a box support, a fulcrumed lever, a pressure equalizing frame capable of operation by said lever and of lateral movement relatively thereto, a pivotal connection between said frame and each of said cover pressing members and means for limiting the pivotal movement between said frame and said cover pressing members.

3. In a box press a box support, a pair of cover pressing members overhanging said support and movable to and from the same, an equalizing frame substantially oblong in plan and pivotally connected at its opposite ends to said pressing members, a threaded socket at each end of said frame and disposed with their bores longitudinally thereof, a threaded bolt adjustable within each of said sockets and one capable of coöperating with each of said pressing members for limiting the pivotal movement between the opposite end of said frame and each of said members, an operating lever extended at right angles to said frame and coöperating therewith for imparting movement thereto, and a connection between said lever and frame whereby the frame is capable of pivotal movement relatively to the lever and at right angles thereto.

In testimony whereof I have signed my name to this specification in the presence of two subscribing witnesses.

DONALD PARKER.
